(57) **CLAIM**

The ornamental design for a camping pot as shown and described.

DESCRIPTION

1. Camping pot
- 1.1 : Perspective
- 1.2 : Perspective
- 1.3 : Front
- 1.4 : Back
- 1.5 : Left
- 1.6 : Right
- 1.7 : Top
- 1.8 : Bottom
- 1.9 : Perspective view shown with the cover in an opened position
- 1.10 : Enlarged

The broken lines in the reproductions depict portions of the camping pot that form no part of the claimed design; fig. 1.10 is the enlarged view of the portion taken at line 1.10 in fig. 1.1; the dash dot dash broken lines in the reproductions represent boundaries for the enlarged view and form no part of the claimed design; the bracket in fig. 1.9 shows the association of elements and forms no part of the claimed design.
